Primary Examiner — Paula Allen Greene*(74) Attorney, Agent, or Firm* — Wood Herron & Evans LLP(57) **CLAIM**

The ornamental design for a cremation urn, as shown and described.

DESCRIPTION

FIG. 1 is a front view of our new, original, and ornamental design for a cremation urn, the back view, left side view, and right side view thereof being the same shape as the front view, the pattern of the surface ornamentation repeats around the circumference of the cremation urn; and, FIG. 2 is a top view thereof.

The unshown portions of the article form no part of the claimed design.
